United States Patent Office

Des. 212,658
Patented Nov. 5, 1968

212,658

HAIR COMB OR SIMILAR ARTICLE

George H. Kress, Newark, N.J., assignor to American Corporation, New York, N.Y., a corporation of Delaware

Filed Nov. 20, 1967, Ser. No. 9,480

Term of patent 14 years

(Cl. D86—8)

FIG. 1 is a front elevational view of a hair comb or similar article showing my new design, the opposite side being a mirror image of the side which is shown;

FIG. 2 is a top plan view thereof;

FIG. 3 is a bottom plan view thereof;

FIG. 4 is an end elevational view of the bottom end of the comb in FIG. 1; and

FIG. 5 is an end elevational view of the top end of the comb in FIG. 1.

I claim:

The ornamental design for a hair comb or similar article, substantially as shown and described.
